UNITED STATES PATENT OFFICE.

SPURGEON HEWITT, OF BRIDGEPORT, CONNECTICUT.

SCREEN-DOOR BRACE.

Application filed November 11, 1920. Serial No. 423,293.

To all whom it may concern:

Be it known that I, SPURGEON HEWITT, a citizen of the United States of America, residing at Bridgeport, in the county of Fairfield and State of Connecticut, have invented new and useful Improvements in Screen-Door Braces, of which the following is a specification.

The object of the invention is to provide a simple, inexpensive and efficient means for bracing a screen door or like structure to guard against or correct the sagging of the free edge thereof and thus restore and maintain the rectangular form of the frame to the end that it may accurately fit and close into the door opening, and more especially to provide a device for the purpose indicated which may be readily applied to a screen door after the use of the latter has resulted in a distortion of the frame and a sagging of the free edge thereof, the bracing element being constructed as an article of manufacture for application with facility to the frame of the door; and with this object in view the invention consists in a construction and combination of parts of which preferred embodiments are shown in the accompanying drawing, wherein:—

Figure 1 is a view of a brace embodying the invention applied in the operative position to a screen door and showing in dotted lines the position of the elements thereof in the course of applying the same to the frame of a door.

Figure 2 is a detail view enlarged of the brace detached.

The brace consists essentially of a bar 10 adapted for arrangement in diagonal relation to the door frame at the upper inner angle thereof between the hinge rail 11 and the top rail 12 thereof, the extremities of the bar being diagonally disposed or cut with relation to the length of the bar to provide surfaces for contact respectively with the inner edges of said door frame elements or rails and having projecting spurs 13 for engagement with the door frame elements or rails to maintain the bar in proper bracing relation to the angle formed by said rails.

In the construction illustrated the bar consists of sections or members 10^a and 10^b corresponding in construction and dimensions and hinged together at their meeting ends as shown at 14, securing or fastening cleats

15 being carried by the inner end of one of the sections or members and having transverse slots 16 in their extremities which are arranged in overlapping relation with the inner end of the other section or member of the bar, said slots being engaged by thumb screws 17 adapted to be tightened to clamp the sections or members of the bar in their operative or extended relation as shown in full lines in Figure 1.

In applying the sectional members to a door the set screws 17 should be loosened and the brake broken or deflected as indicated by the dotted lines in Figure 1, the spurred remote extremities of said bar sections or members being arranged in contact with the inner edges of the door frame elements or rails 11 and 12, whereupon the straightening of the bar by applying force to the inner ends of the brace sections or members toward the angle between the door rails will serve to raise the free edge of the door frame and at the same time force the terminal spurs 13 into the door frame rails. The tightening of the set screws 17 will then lock the brace in its operative position to properly support the door for free swinging movement.

Having described the invention, what is claimed as new and useful is:—

A brace for screen doors and the like consisting of a bar provided with beveled or obliquely cut terminals for arrangement in contact with the inner edges of the hinge and top rails of a door frame, and with the bar in diagonal relation to said rails, and provided at its beveled extremities with projecting spurs or pins for engaging said door frame rails, said bar consisting of relatively movable sections or members hinged together at their adjacent extremities and means for securing said sections or members in their extended or aligned relation, said means consisting of cleats carried by one of said sections or members in overlapping relation with the adjacent end of the other section or member and provided in said overlapping portions with transverse slots, and set screws passing through said slots and engaging said other section or member.

In testimony whereof he affixes his signature.

SPURGEON HEWITT.
